United States Patent

Des. 237,689
Patented Nov. 18, 1975

237,689

LID FOR A PACKAGING CONTAINER OR THE LIKE

Paul Davis, 18 Parsons Drive, Swampscott, Mass. 01907

Filed July 1, 1974, Ser. No. 484,938

Term of patent 14 years

Int. Cl. D9—07

U.S. Cl. D9—267

FIG. 1

FIG. 2

FIG. 3

FIG. 4

FIG. 5

FIG. 1 is a top plan view of a lid for a packaging container or the like showing my new design;

FIG. 2 is an elevational view thereof;

FIG. 3 is a bottom plan view;

FIG. 4 is an enlarged scale fragmentary cross-sectional view taken along line 4-4 of FIG. 1; and

FIG. 5 is an enlarged scale fragmentary cross-sectional view taken along line 5-5 of FIG. 1.

I claim:

The ornamental design for a lid for a packaging container or the like, as shown and described.
